Technical drawing of a device labeled "FIG. 5". The device is a vertical assembly with a central vertical axis. At the top, there is a circular opening with a ribbed or serrated edge, labeled "18". Below this, there is a vertical slot or channel labeled "15" and "15^a". A large, oval-shaped component, labeled "6", is positioned within this slot. To the left of the central axis, there is a vertical slot labeled "16" and "15^a". Below this, there are two horizontal slots labeled "19" and "20". At the bottom of the device, there is a circular opening with a ribbed or serrated edge, labeled "17". The entire assembly is mounted on a base labeled "7". The drawing is annotated with several numbers: 6, 7, 10, 11, 12, 13, 14, 15, 15^a, 16, 17, 18, 19, 20, and 21. The text "Witnesses" is written at the bottom left.

UNITED STATES PATENT OFFICE.

AUGUST ARENS AND JAMES R. FLETCHER, OF NEW BRITAIN, CONNECTICUT, ASSIGNEES TO THE AMERICAN HARDWARE CORPORATION, OF NEW BRITAIN, CONNECTICUT, A CORPORATION OF CONNECTICUT.

FIRE-DOOR LOCK.

1,094,962.

Specification of Letters Patent. Patented Apr. 28, 1914.

Application filed August 13, 1913. Serial No. 784,470.

To all whom it may concern:

Be it known that we, AUGUST ARENS and JAMES R. FLETCHER, citizens of the United States, residing at New Britain, county of 5 Hartford, State of Connecticut, have invented certain new and useful Improvements in Fire-Door Locks, of which the following is a full, clear, and exact description.

This invention relates to locks of the type 10 employed in connection with "fire doors," and particularly fire doors of the hollow metal type. The device of the present invention aims to provide a device of this character, wherein the parts themselves combine 15 accuracy of operation with simplicity of structure, and wherein these parts are constructed to facilitate to a maximum degree their installation. These and various other advantages will be seen from the detailed specification following, taken in connection 20 with the accompanying drawings forming part thereof and illustrating one preferable embodiment of our invention.

In these drawings Figure 1 is a view in 25 elevation of a hollow metal fire door showing locking mechanism of the present invention incorporated therein, the sides of the door being broken away to disclose the interior arrangement. Fig. 2 is a view in end elevation 30 of the lock mechanism shown in Fig. 1. Fig. 3 is a fragmentary view in elevation of the edge of the door showing the application of the mortise lock thereto. Fig. 4 is a vertical section taken through the edge of the door on the line 4—4 of Fig. 3. Figs. 5, 6 and 7 are detail views of the lock mechanism, 35 Figs. 6 and 7 being respectively horizontal sections on the line 6—6 and 7—7 of Fig. 5. Figs. 8, 9 and 10 are detail views of the 40 gravity locking mechanism. Fig. 11 shows a detail of one of the latch bolts and its connection to the operating bar. Figs. 12, 13, 14 and 15 relate to details of the lock mechanism.

Referring to the drawings by numerals, 1 indicates a hollow metal bore structure, within which the lock mechanism of the present invention is inserted. This lock mechanism is arranged in two assembled 50 units embodying a unit frame carrying a plurality of latching bolts and operating mechanism therefor, which frame is inserted within the hollow door, and a second unit comprising an assembled mortise lock mech-

anism arranged to be inserted within the 55 hollow door from the edge thereof, and to coöperate with the latch bolt mechanism of the first unit, these two units being constructed and arranged for such coöperation.

The first unit of the lock mechanism is 60 mounted upon a metal frame 2, in the form of an angle bar extending vertically of and within the hollow metal door, one flange of this angle bar being designed to rest against the inner face of the jamb edge of the door 65 structure. This flange of the angle frame is provided at a plurality of points with enlargements or bosses 3 internally threaded to receive machine screws 4, which are inserted from the outer jamb edge of the door, 70 and by means of which the frame is drawn to bring its flange flat against the interior faces of the door, so that the bolt mechanism will project therefrom at the proper angle. By providing these enlargements or 75 bosses, a sufficient bearing surface is afforded for the machine screws, so that no other securing means is necessary to hold the lock firm to the interior of the door structure. The jamb edge of the door structure may be 80 counterbored so that the heads of the machine screws 4 may seat therein and be flush with the edge of the door. Secured to the side flange of this angle bar frame at a plurality of points in vertical alinement are 85 journaled guides 5 of sheet metal, which guides are each provided with alined slots 6 in their sides to receive and guide an operating bar 7 designed to coöperate with the latch bolts, as hereinafter described. Seated 90 within these journaled guide plates 5 and over the bar 7, are latch bolts 8 formed preferably of sheet metal and each having an end flange 9 to which is appropriately secured a cylindrical bolt head 10. The edge flange 95 of the bolt frame and the edge of the metal door are both recessed at points in alinement with these bolt heads to permit their projection and retraction therethrough. Each of the bolts 8 is provided with a diagonal or cam slot 11 therein, and the operating bar 7 at such points is provided with a headed stud 12 having an antifriction roller thereon operating in these cam slots 11, so that as this bar 7 moves up and down, the bolts 8 with their bolt heads 10, are projected and retracted. The sides of the journaled guides 100

5 are preferably punched in to provide

guide lugs 14 overlying the outer faces of the bolts 8 and serving to guide them in the proper plane of movement.

The operating bar 7 adjacent the upper 5 and lower portions of the door structure is formed as a single bar. In order to permit the operation of this bar through a mortise lock mechanism such as hereinafter described, it will be evident that means must 10 be provided whereby the lock case of this mechanism may be inserted in proper relation to the operating bar without interfering with the operation of said bar. Therefore, at the point where the lock case of the 15 mortise lock is to be inserted, we give the operating bar a bifurcated formation to provide a pocket within which the lock case may be inserted. This is effected by providing spaced plates 15 having a portion of their 20 sides turned inwardly, as at 15^a, to form a central or bearing flange for the lock case, and having their upper and lower ends, as at 18, turned inwardly, and thence bent to embrace therebetween the upper and lower 25 ends of the operating bar 7. This bar 7 does not extend the entire vertical height of the frame 2, but is cut off at points above and below the point of the mortise lock for connection to the spaced plates 15, which plates 30 form in effect part of the operating bar. The plate 15 located at the exterior side of the bar, is provided with an elongated clearance slot 16 for the cylinder lock, and also with aligned elongated clearance slots 17 to- 35 toward the knob spindles of the mortise lock. The space between the plates 15 is greater than the width of the lock case, and is provided to give space for plates 19 secured to the inner faces of the spaced plates 15 at 40 aligned points and each provided with abutment flanges 20. These abutment flanges are designed to coöperate with the mortise lock mechanism and form a means whereby the operating bar 7 is moved to retract the latch 45 bolts.

The mortise lock forming the second unit of this lock mechanism is inserted from the jamb edge of the door, the jamb edge of the door structure being cut away at this point 50 and the face plate 22 of this lock being secured to bosses or enlargements 23 formed on the edge flange of the lock frame 2 by means of suitable screws. The lock case 21 of the mortise lock extends inwardly from 55 the edge of the door and in between the spaced plates 15 and into the pocket formed thereby. This mortise lock mechanism is of a standard type and is inserted within the door as above described, the knobs and their 60 spindles being subsequently inserted through suitable openings formed in the front and rear sides of the door structure, these spindles extending through the clearance slots 17 in plates 15 and connecting with the 65 latch bolt mechanism of the mortise lock in

the usual manner. The usual escutcheon plates 24 are provided on the outer face of the door and the usual cylinder lock mechanism 25 is inserted through a suitable opening formed in one of the escutcheon plates 70 and in the door structure, this cylinder extending through the clearance slot 16 and securing into the lock case 21 in the usual manner. We should add that the clearance slots 16 and 17 are provided to permit the 75 movement of the plates 15 of the operating bar relative to the parts of the mortise lock mechanism inserted therethrough.

Means are provided for moving the operating bar 7 through the turning of the 80 knobs to retract the latch bolt of the mortise lock. These means preferably take the form of roll-backs 30, whose hubs 29 are suitably secured to the hubs 28 of the knob spindles, as by screws, so that these roll-back members 85 will be positioned at the outer side of the lock case between said case and the inner faces of the plates 15 and in a plane with the abutment flanges 20. By the operation of the knob spindle to retract the latch bolt of the 90 mortise lock, it will be evident that the roll-back members 30 will be turned to engage the abutment flanges, raise the spaced plates 15 and operating bar 7, so that their studs 12 and antifriction rollers 13 will act against 95 the cam slots 11 of the spaced bolts and retract said bolts in this direction of movement of the operating bar. This operating bar with its plates 15 is normally moved downwardly by gravity, so that the bolts 100 controlled thereby are projected. The operation of the knob of the mortise lock to retract its own latch bolt therefore serves to move the operating bar to retract the spaced latch bolts also.

In a device of this character it is preferable to provide means whereby the operating bar and its latch bolts are retained in retracted position when the bar has been moved to retract these bolts and when the 110 door has been opened. To this end, we provide a gravity-controlled latching device carried by the lock frame 2 and coöoperating with the upper end of the bar 7 to effect this result. This latching device is preferably 115: constructed as follows: Secured to the angle frame 2 is a housing 31, within which is pivotally mounted an auxiliary latch 32 connected at a point adjacent its pivoted end, as at 33, with one end of a locking slide 34. 120: Mounted on a stud 35 above this latching slide is a bell crank lever whose upper end 36 is weighted and whose lower end 36^a is provided with an elongated slot therein guiding upon a stud 38 projecting from the 125 side of the locking slide 34. This locking slide is guided and limited in its movement by means of a pin 39 projecting from the lock frame 2 and guiding in a slot 40 in said bar. The edge of the operating bar 7 130

is provided with a plurality of stepped recesses forming holding shoulders 41 and 42, the latter extending a greater distance from the edge than the former. A holding stud 43 extends from the rear face of the locking bar 34, and, when the operating bar 7 is raised to retract the latch bolts, as hereinbefore described, this stud 43 will engage with one of the shoulders 41 or 42 of the bar 10 to hold the bar in raised position. This is effected as follows: The weight of the bell crank lever acting against the stud 38 of the locking bar normally presses the bar outwardly toward the edge of the door and in a direction to bring its stud 43 against the edge of the operating bar 7. In so doing, it projects the latch bolt 32 beyond the jamb edge of the door. When the door is closed, this latch bolt 32 will engage the flush face of the door casing and be forced inwardly, thereby moving the lug 43 of the locking bar away from the edge of the operating bar 7, when the knob of the mortise lock is operated to raise the operating bar 7 and retracted to raise the operating bar 7 and retract the latch bolts controlled thereby. This will bring one of the shoulders 41 or 42 opposite and in line with the upper edge of the lug 43, so that when the door is opened the weighted bell crank lever will project the latch 32 and will bring the lug 43 under one of the two locking shoulders 41-42 which have been raised to a position in line with this lug by the latch retracting movement of the bar. As long as the door 35 remains open, the weight of the bell crank lever will hold the lug 43 in engagement with one of these shoulders and thereby retain the operating bar in bolt-retracting position, but as soon as the door is closed, the latch 32 is forced inwardly by the flush face of the door jamb and will move the lug 43 from engagement with the shoulder, whereupon the operating bar 7 will move downwardly by gravity, projecting the latch 40 bolts. We provide two shoulders 41 and 42 so that in the event the knob is not given a full turn to fully retract the latch bolts, the operating bar will nevertheless be locked. In practice, a clearance of a fraction of an 50 inch is allowed between the edge of the door and the door jamb. In case a timid person only partially turns the knob but sufficiently to withdraw the latch bolts far enough for door opening, the operating bar 7 will have 55 its shoulder 41 engaged by the locking lug 43. If a complete turn is given the knob, the second shoulder 42 will be positioned opposite the lug 43 and the operating bar held under these conditions also.

60 We have described the roll-back members 30 as carried by the lock case 21 and secured to the hubs of the knob spindles, so that they are operated by the turning of the knob spindle. It will be evident, however, that 65 these roll-backs need not be carried by the

lock case, but may be journaled for instance in the lock frame 2, and operated by the knob spindles in the same manner. The construction first described is, however, the preferable one.

70 While we have herein described a preferable embodiment of our invention, we desire it understood that various changes in structure and relative arrangement of parts is possible within the spirit of the invention 75 and the scope of the appended claims.

What we claim is:

1. A lock mechanism for hollow door structures comprising in combination a frame mounted within said door, a plurality of spaced latch bolts carried by said frame, a common operating connection for said bolts, an assembled lock mechanism independent of said frame and including a bolt and means for projecting and retracting the same, said lock mechanism extending inwardly of said door edge and coöperating with said operating connection to control said latch bolts.

2. A lock mechanism for hollow door structures, comprising in combination a frame mounted within and extending vertically of said door, a plurality of spaced latch bolts carried by said frame, a common operating connection for said bolts, means normally tending to project said bolts, an assembled lock mechanism independent of said frame and including a bolt and means for projecting and retracting the same, said mechanism extending inwardly of said door edge and being arranged and positioned to coöperate with said operating connection to retract said latch bolts upon the retraction of its own bolt.

3. A lock mechanism for hollow door structures, comprising in combination a frame mounted within and extending vertically of said door, a plurality of spaced latch bolts carried by said frame, a common operating connection for said bolts, means normally tending to project said bolts, an assembled lock mechanism independent of said frame and including a bolt and means for projecting and retracting the same, said mechanism extending inwardly of said door edge and being arranged and positioned to coöperate with said operating connection to retract said latch bolts upon the retraction of its own bolt, and means operable upon the retraction of said latch bolts and the opening of the door to automatically hold said operating connection in bolt-retracted position and operable upon the closing of the door to release said connection whereby said latch bolts may be projected.

4. A lock mechanism for hollow door structures, comprising in combination a frame mounted within and extending vertically of said door, a plurality of spaced latch bolts carried by said frame, a com-

mon operating connection for said bolts, an assembled knob-controlled lock mechanism independent of said frame and latch bolts and extending inwardly of the edge of said door, said lock mechanism being detachably secured to said frame and being arranged and positioned relative thereto to coöperate with the operating connection of said latch bolts to operate said bolts upon its operation 10 through said knob control.

5. A lock mechanism for hollow door structures, comprising in combination a frame mounted within and extending vertically of said door, a plurality of vertically spaced latch bolts carried by said frame, a common operating connection for said bolts, said connection being shaped to provide a pocket, means normally tending to project said bolts, an assembled mortise lock mechanism, including a knob-controlled latch bolt, independent of said frame and extending inwardly from the edge of said door and within said pocket, said mortise lock mechanism being detachably secured to said frame 20 and being arranged to coöperate with said operating connection to operate its bolts upon the retraction of the latch bolt of said mortise lock.

6. A lock mechanism for hollow door structures, comprising in combination, a frame mounted within and extending vertically of said door, a plurality of vertically spaced latch bolts carried by said frame, a reciprocating operating member carried by 30 said frame and common to and in operative connection with each of said bolts, said member being normally positioned by gravity to project said bolts and being formed with a pocket and an abutment, an assembled mortise lock mechanism including a knob-controlled latch bolt independent of 40 said frame and extending inwardly from the edge of said door and within said pocket, a roll-back member coöoperating with said abutment and operated by latch bolt re- 45 tracting movement of a knob of said mortise lock to actuate said operating member in a direction to retract said plurality of latch bolts.

50 7. A lock mechanism for hollow door structures, comprising in combination, a frame mounted within and extending vertically of said door, a plurality of vertically spaced latch bolts carried by said frame, a reciprocating operating member carried by 55 said frame and common to and in operative connection with each of said bolts, said member being normally positioned by gravity to project said bolts and being formed 60 with a pocket and an abutment, an assembled mortise lock mechanism including a knob-controlled latch bolt independent of said frame and extending inwardly from the edge of said door and within said pocket, 65 a roll-back member coöoperating with said

abutment and operated by latch bolt re- 70 tracting movement of a knob of said mortise lock to actuate said operating member in a direction to retract said plurality of latch bolts, and means carried by said frame and coöperating with said operating member to automatically engage the same upon bolt-retracting movement thereof and the opening of the door to hold said member in bolt-retracting position, and operable upon the 75 closing of the door to automatically release said member whereby said bolts are projected thereby through gravity.

8. A lock mechanism for hollow door structures, comprising in combination a flanged metal frame mounted within and against the edge of said door and extending vertically thereof, a plurality of vertically spaced latch bolts carried by said frame, a reciprocating operating bar carried by said frame and including a bifurcated portion forming a pocket and complement abutments, means of operative connection between said bar and each of said latch bolts including cam slots and coöperating studs 80 whereby movement of said bar projects and retracts said latch bolts, said bar being normally positioned by gravity to project said bolts, an assembled mortise lock mechanism including a latch bolt and oppositely disposed knobs and spindles, said lock mechanism having its face plate detachably secured to said frame and its lock case extending within said operating bar pocket, an operating roll-back member coöoperating 85 with each of said abutments, and means of connection between said knobs and said roll-back members whereby latch-retracting movement of a knob operates a roll-back member to engage its abutment and move 90 said operating bar in a direction to retract said latch bolts.

9. A lock mechanism for hollow door structures, comprising in combination a flanged metal frame mounted within and against the edge of said door and extending vertically thereof; a plurality of vertically spaced latch bolts carried by said frame, a reciprocating operating bar carried by said frame and including a bifurcated portion forming a pocket and complement abutments, means of operative connection between said bar and each of said latch bolts including cam slots and coöperating studs 100 whereby movement of said bar projects and retracts said latch bolts, said bar being normally positioned by gravity to project said bolts, an assembled mortise lock mechanism including a latch bolt and oppositely disposed knobs and spindles, said lock mechanism having its face plate detachably secured to said frame and its lock case extending within said operating bar pocket, an operating roll-back member coöoperating 105 with each of said abutments, and means of connection between said knobs and said roll-back members whereby latch-retracting movement of a knob operates a roll-back member to engage its abutment and move 110 said operating bar in a direction to retract said latch bolts.

115 10. A lock mechanism for hollow door structures, comprising in combination a flanged metal frame mounted within and against the edge of said door and extending vertically thereof; a plurality of vertically spaced latch bolts carried by said frame, a reciprocating operating bar carried by said frame and including a bifurcated portion forming a pocket and complement abutments, means of operative connection between said bar and each of said latch bolts including cam slots and coöperating studs 120 whereby movement of said bar projects and retracts said latch bolts, said bar being normally positioned by gravity to project said bolts, an assembled mortise lock mechanism including a latch bolt and oppositely disposed knobs and spindles, said lock mechanism having its face plate detachably secured to said frame and its lock case extending within said operating bar pocket, an operating roll-back member coöoperating 125 with each of said abutments, and means of connection between said knobs and said roll-back members whereby latch-retracting movement of a knob operates a roll-back member to engage its abutment and move 130 said operating bar in a direction to retract said latch bolts.

nection between said knobs and said roll-back members whereby latch-retracting movement of a knob operates a roll-back member to engage its abutment and move said operating bar in a direction to retract said latch bolts, and an automatic gravity-controlled latching device coöperating with said bar and door casing to engage and hold said bar in bolt-retracted position upon the retraction of said bolts thereby and the opening of the door, and operable upon the closing of the door to release said bar whereby said bolts are projected thereby.

10. A lock mechanism of the character described, embodying two separate and assembled units, one of said units comprising a lock frame arranged for insertion within a hollow door structure and carrying a plurality of bolts and a common operating connection therefor, and the other of said units embodying a lock mechanism including a manually controlled bolt, said mechanism being arranged for insertion within said door structure to coöperate with the operating connection of said bolts to operate said bolts coincident with the manual operation of its own bolt.

11. A lock mechanism of the character described, embodying two separate and assembled units, one of said units comprising a metal frame arranged for insertion within and connection to a hollow door to extend vertically thereof, said frame carrying a plurality of spaced latch bolts and a common operating connection therefor, and the other of said units embodying a mortise lock mechanism including a knob-controlled latch bolt arranged to be inserted within said door structure and to be operatively connected to said bolt operating connection of the first unit by the insertion of a knob spindle.

12. A lock mechanism of the character described, embodying two separate and assembled units, one of said units embodying a metal frame arranged for insertion within and connection to a hollow door to extend vertically thereof, said frame carrying a plurality of vertically spaced bolts and a common operating connection therefor provided with a pocket therein and with an abutment, and the other of said units embodying a mortise lock mechanism including a latch bolt and a knob and spindle arranged to retract the same arranged to be inserted within said door structure from the edge thereof and to extend within said pocket, said knob spindle being arranged to coöperate with said operating connection and said abutment upon latch-retracting movement thereof, to operate said connection to retract said latch bolts.

13. As an article of manufacture, a flanged metal lock frame arranged for insertion within a hollow door structure to extend vertically thereof and having one of its

flanges arranged for connection to the jamb edge of a door structure, said flange being provided with a plurality of vertically spaced bosses and with threaded bores extending through said bosses arranged to receive attaching machine screws.

14. In a lock of the character described, a plurality of spaced bolts, an operating member operatively connected with each of said bolts and normally tending to project the same by gravity, manually-controlled means for actuating said operating member to retract said bolts, and a gravity actuated latching device coöperating with said operating member to engage and hold the same against movement at a plurality of predetermined bolt-retracting positions.

15. In a lock of the character described, a plurality of spaced bolts, an operating bar operatively connected with each of said bolts and normally tending to project the same by gravity, said operating bar having one edge recessed to provide a plurality of locking shoulders at progressively greater distances from its edge, manually-controlled means for moving said operating bar to retract said bolts, and a gravity-controlled slide having a locking abutment normally tending to engage with said locking shoulders at different points of bolt-retracting movement of said bar, said slide having connections coöperating with the door casing to move said slide from holding engagement with said bar upon the closing of the door whereby said bolts may be projected by gravity through said operating bar.

16. A lock mechanism for door structures comprising, in combination, a latch bolt mechanism seated within the door structure and including a latch bolt and an operating connection therefor, an assembled lock mechanism independent of said latch mechanism and including a bolt, and means for projecting and retracting the same, said lock mechanism including means arranged for operative connection with the operating connection of said latch mechanism to operate its bolt.

17. A lock mechanism for door structures comprising, in combination, a latch mechanism seated within said door structure and including a plurality of latch bolts and operating connections therefor, an assembled lock mechanism independent of said latch mechanism and including a bolt, and means for projecting and retracting the same, said lock mechanism including means arranged for operative connection with the operating connections of said latch mechanism to operate the latch bolts thereof.

18. A lock mechanism for hollow door structures comprising, in combination, a latch bolt mounted within said hollow door structure and having an operating connection therefor, an assembled lock mechanism,

including a bolt and means for projecting and retracting the same, said lock mechanism being independent of said latch bolt and including means arranged to be operatively positioned within said hollow door to coöperate with the operating connection of said latch bolt to operate said bolt.

19. A lock mechanism of the character described, embodying two separate and independent assembled units, one of said units comprising a plate arranged for insertion within a hollow door structure and carrying a latch bolt and an operating connection therefor, and the other of said units embody-

ing a lock mechanism including a manually controlled bolt, said lock mechanism being arranged for insertion within said door structure and including means arranged to be positioned to coöperate with said latch bolt mechanism whereby said latch bolt is controlled coincidentally with the manual control of said lock bolt.
